UNITED STATES PATENT OFFICE

WILLIAM LEWIS EVANS, OF WASHINGTON, INDIANA

HINGE

Application filed October 19, 1928. Serial No. 313,529.

This invention relates to hinges such as those used on "vanishing doors" of the type shown in my U. S. Patent Nos. 1,367,954; 1,412,107; 1,412,108; 1,412,109; 1,407,739; 1,407,740; 1,407,790; and 1,489,633, and, among other objects, aims to provide improved strong and durable hinge joints which are accurately fitted and can be made at a relatively low cost.

10 In the accompanying drawings,—

Fig. 1 is a top plan view showing a compound floor or ceiling hinge having the preferred form of hinge joints;

15 Fig. 2 is a sectional view, drawn on an enlarged scale and taken on the line 2—2 of Fig. 1;

Fig. 3 is a top plan view showing another type of compound hinge embodying the improvements.

20 Compound hinges like those shown in my aforesaid patents have not been sufficiently strong to support extra heavy doors without permitting them to sag. It has also been found that ordinary hinge joints, unless they 25 are very accurately fitted, are so loose that liquid will enter them during the plating process and thereby bind the hinge pins in their sockets. This invention aims to provide improved accurately fitted joints or 30 terminals and sockets constructed and arranged to prevent the water from entering the joints when the hinges are being plated and adapted to support extra heavy doors without sagging.

35 Referring to Fig. 1, the present invention is there embodied in a compound floor hinge of the same general type as that shown in my aforesaid Patent No. 1,489,633 which comprises a door plate 10, a pair of round floor plates or feet 11 and Z-shaped arms 12 hingedly mounted in terminal sockets in said plate and said feet.

40 Herein the plates are die castings of brass, the door plate having drilled and reamed terminal sockets 13 at its opposite ends. Similar terminal sockets 14 are provided in the up-standing bosses 15 on the feet and terminate in enlarged recesses 16 in the bases, these feet being quite similar to those shown in my 45 aforesaid patent.

In accordance with the present invention, the hinge arms or rods, which are preferably made of Bessemer steel, have specially formed terminals 17 to fit in said sockets, the arms being reduced in suitable heavy and powerful die presses (not shown) so that they present shoulders 18 at their inner ends. The diameter of these terminals is made approximately two thousandths (.002) of an inch less than that of the reamed sockets to afford just enough clearance to permit the hinges to work freely. After the terminals are reduced, they are trimmed or cut off to the proper lengths.

To provide thrust bearings for the hinge arms 12 and to divide the load between upper and lower hinges, pairs of washers 19 are shown as being fitted and secured on the terminals at the opposite ends of the socket members. All of the washers are conveniently the same and are preferably punched out so their openings fit the terminals very closely. The shoulder washers are first pushed on the pintles; then, the terminals are placed in their respective sockets; the end washers are then inserted on the projecting ends of the terminals and secured thereon by spinning the extreme ends of the terminals to provide enlarged heads 20. The spinning operation is advantageous because it does not upset the terminals within the sockets and cause them to bind. Moreover, the ends can be spun until the bearing faces of each pair of the washers barely clear the ends of the socket members but without binding. This 50 construction also serves to prevent water from entering the bearings during the plating process.

In Fig. 3 there is shown a compound hinge of the same general type as that shown and claimed in my Patent No. 1,407,790. This hinge differs from that shown in Fig. 1 in that it is adapted to be secured to the door jamb instead of the floor or ceiling, and the distances between the sockets in the two plates are different so that the door may swing in a different manner. In this instance, there is a relatively short door plate 10' and an angle bracket or plate 11' to which the hinge arms 12' are hinged by means of the same type of 55

hinge joints as those in the door plate shown in Fig. 1.

Practical use of hinges embodying this invention has demonstrated that they work very easily without binding; that they will support very heavy doors without permitting them to sag, and they will not easily break or get out of order. Further, a very great economy in their manufacture is made possible because die casting and stamping operations are utilized.

Obviously, the present invention is not restricted to the particular embodiment thereof herein shown and described.

15 What I claim is:—

1. In a multiple pivot hinge of the character described, plate members providing means to secure the hinge to a door; vertical bearing sockets drilled through said plate members and of uniform diameter throughout their lengths; Z-shaped bars having vertical, parallel arms; reduced terminals formed on said arms extending through the bearing sockets and presenting shoulders at 25 their inner ends; closely fitting washers on the reduced terminals between the shoulders and the bearing sockets providing end thrust bearing elements; closely fitting washers on the outer ends of said terminals also providing end thrust bearing elements; and heads formed on the ends of said terminals providing integral shoulders for the last mentioned washers and holding the washers in close contact with the ends of the bearing 35 sockets.
2. In a multiple pivot hinge of the character described, an elongated plate adapted to be secured to a door; spaced, vertical bearing sockets drilled through the plate adjacent to 40 its ends; Z-shaped bars having vertical parallel arms; reduced terminals on one arm of each bar projecting through and closely fitted in the bearing sockets; shoulders at the inner ends of said reduced terminals; plate washers 45 closely fitted on said terminals between the inner ends of said shoulders providing end thrust bearing elements to sustain a portion of the weight of the door; washers also closely fitted on the end portions of said terminals 50 to provide other end thrust bearing elements; spun heads on the extreme ends of said terminals to hold said arms assembled on the plate; and supporting members having similar socket bearings secured to the other arms 55 of said bars.

In testimony that I claim the foregoing as my own, I have hereto affixed my signature.

WILLIAM LEWIS EVANS.
